UNITED STATES PATENT OFFICE.

ENOCH F. DRAKE AND ALFRED C. WAIT, OF SALINA, KANSAS.

THILL-COUPING.

SPECIFICATION forming part of Letters Patent No. 391,519, dated October 23, 1888.

Application filed March 30, 1888. Serial No. 269,017. (No model.)

To all whom it may concern:

Be it known that we, ENOCH F. DRAKE and ALFRED C. WAIT, of Salina, in the county of Saline and State of Kansas, have invented a new and useful Improvement in Thill or Pole Couplings, of which the following is a specification.

This invention contemplates certain improvements in thill or pole couplings, having for its object to overcome all rattling, in common with others, and to effectively and securely hold the thill or pole against accidental displacement or detachment, which is liable to occur in consequence of the jarring action to which it is subjected from the motion of the vehicle; and the invention consists of the detailed construction and combination of parts, substantially as hereinafter set forth and pointed out in the claims.

20 In the accompanying drawings, Figure 1 is a vertical longitudinal section of a thill or pole coupling embodying our invention. Fig. 2 is a transverse section taken on the line $x-x$ of Fig. 1. Fig. 3 is a horizontal section taken 25 on the line $y-y$ of Fig. 1, and Figs. 4, 5, 6, 7, and 8 are enlarged detail views of the invention.

In carrying out our invention we employ a clip, A, of usual construction, for application 30 to the front axle, being held thereon by a slotted plate, a , applied to the under side of the axle, and through which pass screws pendent from the clip and fitted with nuts. Upon the front side of the clip A is formed a socket, B, 35 which is open at its upper end and front side. This socket comprises two cheek-pieces, b , each of which is thickened, as at b' , upon its inside rearward a suitable distance, providing, between shoulders b^2 thus formed and the clip 40 A, vertical grooves b^3 b^3 . In the thickened portions b' b' of the cheek-pieces b b are formed semicircular recesses or seats b^4 b^4 , arranged directly opposite to each other and opening at their inner and rear sides into the thill-iron 45 passage b^5 and the vertical grooves b^3 b^3 , respectively.

C is a thill or pole iron, the longer portion of which extends through the passage b^5 , while its cross-head as it is put into position is first 50 passed into the vertical grooves b^3 b^3 downward, and then drawn into the recesses or seats b^4 b^4 , where it normally rests.

D is an elastic or rubber block or cushion inserted into the socket B, with its ends entering and resting in the grooves b^3 b^3 , and which 55 effects the immediate holding in place noiselessly of the thill-iron. The cushion or block D has secured to its top or upper edge a plate, c , which is grooved or channeled, as at c' , in its under side to receive two latches, d d , while 60 to the upper side of said plate is applied an open-ended semi-cylindric casing, e , within which are contained two push rods or plugs, f f . The plate c is provided with a forwardly-projecting tongue, c^2 , which enters and closes 65 the upper portion of the thill or pole iron passage b^5 , excluding flying or falling dirt or other foreign substance from the thill or pole socket. The latches d d have their inner ends turned upward, as at d' d' , at right angles to 70 their other portions, and enter a slot, g , in the plate c , and are acted upon by a spring, h , interposed between and connected to the same. The outer ends of the latches d d are caused to project normally beyond the casing e and the block D by the action of the spring h , and engage with or enter notches or 75 recesses i i in the side walls of the grooves b^3 b^3 . The push rods or plugs f f have their outer ends held beyond the ends of the casing e , also by the action of the spring h . The push rods or plugs, which are cylindric, the greater portion of their lengths, have their remaining or outer portions made rectangular and somewhat reduced, while the casing or 80 inclosure e is slightly contracted at the ends, the object of which is to prevent the endwise displacement of the push rods or plugs. The push rods or plugs f f are disposed in place in the case through its open or bottom side before securing the casing to the cushion or block 85 D, the cylindric or larger portions thereof being arranged at points inward from the contracted or end portions of the casing. The cushion or block D, it will be seen, not only 90 serves as a bearing for the rear or inner end of the thill or pole iron, but also to prevent the cross-head of the thill or pole iron leaving its recesses or seats in the thill or pole socket, while at the same time all tendency to 95 upward displacement of the cushion or block by the thill or pole is prevented, the cushion or block fitting in behind the thill or pole iron and the latter pressing squarely against the 100

cushion and in the direction of its transverse section or at right angles to its plane of displacement, whereby the thill or pole iron will be securely and effectively held in place. The 5 block or cushion D, having no upward pressure exerted upon it, is readily held in place by the latches d d against accidental displacement from the jarring action of the vehicle and its thills or pole, while the cushion or 10 block can be readily removed by simply pushing inward upon the push rods or plugs f f, effecting the retraction or withdrawal of the latches d d from their notches or recesses in the thill or pole iron socket, and lifting the 15 block or cushion out of said socket. It can be as readily replaced by grasping it so as to push the push rods or plugs inward, thus holding the latter until the latches in the block or cushion, which is introduced into its proper 20 place in the thill-socket, have passed below the upper edges of the cheek-pieces of the thill or pole socket. The block or cushion is continued to be pressed down into its socket until the latches spring into their notches, and 25 thus arrest further movement of the block or cushion and effect the holding of the same in place.

Having thus fully described our invention, what we claim, and desire to secure by Letters Patent, is—

1. In a thill-coupling, the thill-iron socket having its cheek or side pieces thickened upon the inside, which thickened portions are provided with recesses or seats and which combine with the cheek-pieces and the axle-clip to form vertical grooves in a plane in rear and at the sides of said recesses or seats, in combination with the thill-iron having its cross-head resting in said recesses or seats, and the cushion 35

ion fitting in said grooves immediately behind 40 said cross-head and having applied to its upper end spring-actuated latches engaging notches or recesses in the side walls of said grooves, substantially as specified.

2. In a thill or pole coupling, the combination, with the thill-iron socket having its cheek or side pieces provided with vertical grooves, of the block or cushion having applied to its upper end a plate, and the latches with their outer ends projecting beyond the plate and cushion, 45 while their inner portions or ends are extended upward at right angles to their other portions and acted upon by a spring interposed between said inner portions and the push rods or plugs adapted to effect the retraction of said latches, 50 substantially as set forth.

3. The thill or pole coupling comprising the thill-iron socket, having its cheek-pieces enlarged upon the inside, which enlargements are provided in their rear ends with seats or 55 recesses for the reception of the cross-head of the thill-iron, said cheek-pieces also having vertical grooves in rear of said enlargements, the cushion or block having applied to its upper end a plate provided in its under side with 60 a channel or groove, spring-actuated latches fitting in said groove or channel, and the push rods or plugs disposed in a casing or inclosure applied to said plate, said push rods or plugs being held against the inner ends of said latches 65 and endwise displacement in said casing, substantially as specified.
